CROSS TUBE STRADDLE TYPE OF STEAM
GENERATOR FURNACES

John Phillips Badenhausen, Philadelphia, Pa.

Application April 6, 1946, Serial No. 660,247

5 Claims. (Cl. 122—326)

1

This invention relates to steam generating furnaces and more particularly to improvements in furnaces suitable for use in burning fuel of varied types and sizes. This invention further relates to steam generator furnaces in which a gas producer action is effected with subsequent combustion of the combustible gas in an improved manner.

In accordance with the present invention improved provisions are made for the introduction of the fuel and air and the removal of the non-combustible portions or ash resulting from the burning of the fuel.

In accordance with the present invention, also, an improved character of arch construction is provided for promoting the combustion of the combustible gas constituents separated and produced below the arch.

Other advantageous features of the invention will be apparent from the specification and claims.

The nature and characteristic features of the invention will be more readily understood from the following description, taken in connection with the accompanying drawings forming part hereof, in which:

Figure 1 is a longitudinal sectional view through a preferred embodiment of the invention, taken approximately on the line 1—1 of Fig. 2;

Fig. 2 is a vertical transverse sectional view taken approximately on the line 2—2 of Fig. 1;

Fig. 3 is a horizontal sectional view taken approximately on the line 3—3 of Fig. 2;

Fig. 4 is an enlarged view, partly in elevation and partly in vertical central section, of a screw forming part of the present invention;

Fig. 5 is a transverse sectional view of the screw shown in Fig. 4 and taken approximately on the line 5—5 of Fig. 4;

Fig. 6 is a sectional view, enlarged, taken approximately on the line 6—6 of Fig. 2;

Fig. 7 is a sectional view taken approximately on the line 7—7 of Fig. 2; and

Fig. 8 is an enlarged fragmentary view, in elevation of a portion of a screw, forming part of the present invention, for providing uniform withdrawal of ash.

It should, of course, be understood that the description and drawings herein are illustrative

2

merely, and that various modifications and changes may be made in the structure disclosed without departing from the spirit of the invention.

Referring now more particularly to the drawings, in which a preferred embodiment of the invention is illustrated, the steam generator furnace preferably includes a vertical front wall 10, a vertical rear wall 11, vertical side walls 12 and 13, a top wall 14, within which a steam and water drum 15 is centrally and longitudinally disposed, and a front bottom wall 16 of a peculiar shape as hereinafter explained.

Spaced forwardly from the rear wall 11, and upwardly extending, a centrally disposed transverse bridge wall 17 is provided which functions as the rear boundary of a gas generating and combustion space.

The front wall 10 is provided, intermediate the top and bottom thereof, with suitable fuel supplying apparatus 18 for delivering fuel onto a horizontal bed in the space between the front wall 10 and the bridge wall 17 and between the side walls 12 and 13. The fuel supplying apparatus 18 may be of any preferred type but is preferably such as that shown in my application for Letters Patent filed September 25, 1944, Serial No. 555,627, now abandoned and January 20, 1947, Serial No. 723,042, now abandoned.

Each of the side walls 12 and 13 comprises, at the lower part, an upwardly extending portion 19 of refractory material formed integral with the bottom wall 16 and on which a pair of lower water headers 20 and 21 are supported.

The lower water header 20 is connected to the steam and water drum 15 by a bank of steam generating riser tubes 22 which extend from the lower water header 20 upwardly along the side wall 12, as at 22a, then transversely and with an upward inclination as at 22b, to the side wall 13, then vertically upwardly along the side wall 13, as at 22c, and then across the interior of the top wall 14, as at 22d, to the steam and water drum 15. The lower water header 21 is preferably connected to the steam and water drum 15 by a bank of tubes 23 disposed in alternating relationship with respect to the tubes of the bank of tubes 22 and these tubes 23 extend from the lower water header 21 vertically upwardly, as at 23a, along the side wall 13, then transversely and

45

50

with upward inclination as at 23b to the side wall 12, then vertically upwardly along the side wall 12, as at 23c, and then across the interior of the top wall 14, as at 23d, to the steam and water drum 15. The tubes of the banks of tubes 22 and 23 at the central part where the tube portions 22b and 23b are close together (see Fig. 7) thus providing a screen and preventing upward gas flow at the center, as hereinafter explained. A baffle 25, of refractory material, is provided above the central crossing point of the tube portions 22b and 23b of the banks of tubes 22 and 23, this baffle 25 preferably being of inverted V shape, and extending from the front wall 10 to the bridge wall 17 restricting the flow of combustible gas, as hereinafter explained.

The tubes of the banks of tubes 22 and 23 at junction of the tube portions 22b and 22c, and 23b and 23c and adjacent the side walls 12 and 13 are respectively provided with longitudinally disposed refractory baffle blocks 26 extending from the front wall 10 to the bridge wall 17. The baffle blocks 26 with the central baffle 25, restrict the upward flow of combustible gas, as herein-after explained.

The tubes of the banks of tubes 22 and 23, at the junction of the tube portions 22a and 22b, and 23a and 23b, and adjacent the side walls are also provided with longitudinally disposed refractory baffle blocks 27 for restricting and directing the flow of combustible gas released therebelow. The spaces on each side between the refractory blocks 26 and 27 and between the tube portions 22b and 23b provide air inlet spaces 28a and 28b and an air duct 28 is provided, preferably on the exterior of the front wall 10, for the delivery of air to these spaces for combustion.

A boiler section is provided to the rear of the bridge wall 17 and includes a transverse lower header 30, which is provided, preferably, at the same level as the lower headers 20 and 21. The side wall headers 20 and 21, in the space to the rear of the bridge wall 17, in front of the rear wall 11 and between the side walls 12 and 13, are connected to the steam and water drum 15 by a plurality of steam generating riser tubes 31 which are distributed in this space on each side. The rear header 30 is also connected to the steam and water drum 15 by a plurality of steam generating riser tubes 32 which extend at the central portion forwardly and then in front of the bridge wall 17 with an upward inclination and then vertically upwardly to the steam and water drum 15.

The front bottom wall 16 in front of the bridge wall 17 is preferably provided with one or more screws 35 and has inclined floor portions 16a and 16b for aiding the delivery of ash to the screws 35, as hereinafter explained.

Each of the screws 35, as shown in detail in Figs. 4 and 5, preferably includes a central hollow cylindrical portion 36 with a helical flange 37 extending outwardly therefrom and with a plurality of air delivery openings 38 in the spaces between the convolutions of the flange. The interiors of the screws 35, at their front ends, are in communication with a high pressure wind box 39, which is connected by a duct 40 to a suitable source of air under pressure such as a fan (not shown). The screws 35 are supported at their front ends by drive shafts 42 which are carried in suitable bearings 41 and through which the drive shafts 42 extend for driving the screws 35. The rear ends of the screws 35 to the rear of the bridge wall 17 extend beneath a rear

bottom wall 16c. The screws 35, at their rear ends, are supported in suitable bearings 43 and are in communication with an ash pit 44 for the reception of ash delivered from the furnace. The screws 35 are closed at their ends by end caps 45 which are removable for cleaning.

In the form of screw illustrated in Fig. 8, the central cylindrical portion 36a is provided as in the form illustrated in Figs. 4 and 5, together with air delivery openings 38. The flanges 37a are constructed to increase in diameter in steps or stages towards the discharge end so as to present a larger area for propelling the ash for discharge.

The front wall 10 is provided with suitable access and inspection openings 46, preferably about the level of the fuel bed in the furnace, and with an access opening 47 located above the screws 35.

A gas-tight cover 48 is provided along the side walls 12 and 13 at the lower part thereof, and a similar cover 49 may be provided above the ashpit 44 and the rear ends of the screws 35 for preventing the escape of carbon monoxide gas, hydrogen and other gases distilled from the coal and released in the lower part of the furnace.

The mode of operation will now be pointed out.

Fuel, such as anthracite or bituminous coal of varied sizes or types, coke breeze, wood wastes, combustible refuse, including tar, or the like, is introduced without the necessity of reducing the water content to a low level and distributed over the bed by the fuel supplying apparatus 18 in the space below the transverse sections 22b and 23b of the tubes 22 and 23. Air is introduced through the wind box 39 to the interior of the screws 35

from which it passes through the openings 38 and upwardly through the fuel bed. The quantity of air supplied at this location is restricted so as to provide incomplete oxidation and combustion of the carbon in the fuel and for the production and release of carbon monoxide and distilled gases. The carbon monoxide and distilled gases passing from the fuel bed is guided and divided in its upward passage by the baffles 27 and 25 and passes upwardly in two streams. As it passes the baffles 25 it is met by air delivered thereto for completion of the combustion. The crosswise introduction of the air and the passage of the air and the gas together through the transverse portions 22b and 23b of the banks of tubes 22 and 23 promotes an intimate intermixture of the combustible gas and air thereby aiding in the combustion of the gas released therebelow. The combustible gas preferably burns with a short intense flame just above the upper of the tube portions 22b and 23b. Any small particles of fuel entrained and carried upward by the ascending stream of combustible gas are quickly ignited and burned in these flames. The hot gases of combustion then pass upwardly and rearwardly in contact with the tubes of the banks of the tubes 32 and with the tubes of the banks of tubes 31, and then downwardly for discharge through the openings 50 to the stack (not shown).

The heat released as radiant heat of combustion in the space between the tube portions 22b, 22c, and 22d and the tube portions 23b, 23c, and 23d, above the transverse tube portions 22b and 23b and below the top wall 14 is effective for generating steam for release in the steam and water drum.

The lower portions 22a and 23a of the tubes 22 and 23 are also subjected to heat transfer and absorption of heat released in the conversion of

the fuel to steam. The heat transfer and absorption of heat released in the conversion of the fuel to steam is effective for generating steam for release in the steam and water drum.

The heat released as radiant heat of combustion in the space between the tube portions 22b, 22c, and 22d and the tube portions 23b, 23c, and 23d, above the transverse tube portions 22b and 23b and below the top wall 14 is effective for generating steam for release in the steam and water drum.

The lower portions 22a and 23a of the tubes 22 and 23 are also subjected to heat transfer and absorption of heat released in the conversion of the fuel to steam. The heat transfer and absorption of heat released in the conversion of the fuel to steam is effective for generating steam for release in the steam and water drum.

the combustible portions of the fuel to carbon monoxide.

As the fuel burns, the ash residue at the lower part is directed by the wall portions 16a and 16b to the screws 35 and is moved towards the rear by the screws 35 for discharge to the ash pit 44. The introduction of the air through the screws 35 tends to make the openings 38 self cleaning and contributes to the simplicity of the structure.

I claim:

1. In a steam generator, spaced side walls, a bottom wall at the lower part of said side walls and extending therebetween, an upper steam and water drum centrally disposed with respect to said side walls, lower header means, steam generating tubes connected to said header means and to said drum and each having transversely disposed portions for separating the space between said bottom wall and said steam and water drum into an upper chamber and a lower chamber, said transversely disposed portions extending respectively from one side wall to the opposite side wall and the respective end portions of the transversely disposed tube portions being spaced at the side walls to provide spaces for the introduction of air for intermingling with the combustible gaseous material passing from the lower chamber to the upper chamber, air supply means in communication with said spaces, spaced baffle members mounted on said transverse tube portions for separating the combustible gaseous constituents into a plurality of streams, means for supplying air to the lower portion of said lower chamber, and means for supplying fuel to said lower chamber.

2. In a steam generator, spaced side walls, a bottom wall at the lower part of said side walls and extending therebetween, an upper steam and water drum centrally disposed with respect to said side walls, steam generating tubes connected to said drum and each having transversely disposed portions for separating the space between said bottom wall and said steam and water drum into an upper chamber and a lower chamber, means for supplying fuel to said lower chamber, said transverse portions being inclined and crossing intermediate the side walls, the end portions of the transverse portions being spaced at the side walls to provide spaces for the introduction of air for intermingling with the combustible gaseous material passing from the lower chamber to the upper chamber, air supply means in communication with said spaces, and spaced baffle members mounted on said transverse tube portions for separating the combustible gaseous constituents into a plurality of streams for delivery with the air from said spaces into said upper chamber for combustion.

3. In a steam generator, side walls, a bottom wall, an upper longitudinally extending steam water drum, spaced lower headers extending parallel to said drum, banks of tubes each having a lower portion extending upwardly from one of said headers along the adjoining side wall and having an inclined transversely disposed section intermediate said drum and said headers, each of said tubes having an upper portion extending upwardly along one of the side walls and in communication with said drum, each of said upper portions being respectively disposed on the opposite side from the corresponding lower portion, said transverse tube sections separating the space between said bottom wall and said steam and water drum into an upper chamber and a lower chamber longitudinally disposed, and the respec-

tive end portions of said tube sections providing spaces for the introduction of air refractory members disposed above the central parts of said transverse tube sections, additional longitudinally disposed refractory members disposed adjacent said side walls and providing with said other members restricted passageways for ascending gases passing from said lower chamber to said upper chamber, means for supplying fuel below the level of said transverse tube sections, means for supplying air at the level of said transverse tube sections to said spaces for intermingling with the ascending gases, and means in the lower part of said lower chamber for the delivery of air for partial combustion of the fuel in the lower chamber and the release of combustible constituents for delivery to the upper chamber for combustion.

4. In a steam generator, side walls, a bottom wall, an upper longitudinally extending steam and water drum, spaced lower headers extending parallel to said drum, banks of tubes each having a lower portion extending upwardly from one of said headers along the adjoining side wall and having an inclined transversely disposed section extending substantially horizontally intermediate said drum and said headers, each of said tubes having an upper portion extending upwardly along one of said side walls and in communication with said drum, said transverse portions crossing intermediate the side walls and each of said upper portions being respectively disposed on the opposite side from the corresponding lower portion, said transverse tube sections separating the space between said bottom wall and said steam and water drum into an upper chamber and a lower chamber and the respective end portions of the transverse tube sections providing spaces for the introduction of air, refractory block members disposed above the crossing points of said transverse tube sections, additional refractory block members extending respectively from each of said side walls and providing with said other block members longitudinally disposed restricted passageways for ascending gases passing from said lower chamber to said upper chamber, means for supplying fuel below the level of said transverse tube sections, means for supplying air at the level of said transverse tube sections to said spaces for intermingling with the ascending gases, and means in the lower part of said lower chamber for the delivery of air for partial combustion of the fuel in the lower chamber and for the release of combustible constituents for delivery to the upper chamber for combustion.

5. In a steam generator, spaced side walls, a bottom wall at the lower part of said side walls and extending therebetween, an upper steam and water drum, lower water header means, steam generating tubes extending from said header means and connected to said drum and each having transverse portions extending substantially horizontally and crossing intermediate said drum and said bottom wall, said transverse tube portions extending alternately from said side walls upwardly along the opposite side walls and separating the space between the said bottom wall and said steam and water drum into an upper chamber and a lower chamber, spaced baffle members carried by said tube portions for providing a plurality of vertical passageways between said chambers, means for supplying fuel to the lower chamber, means at the lower part of said lower chamber for supplying air for partial combustion

of the fuel in said lower chamber, and air inlet means in communication with said crossing portions of said tubes for supplying air for delivery to said upper chamber for completion of combustion of combustible gaseous constituents delivered through said passageways.
